HYDRAULIC JACK

Theodore A. Cheesman, Kalama, Wash.

Application September 22, 1947, Serial No. 775,522

2 Claims. (Cl. 60—52)

1

This invention relates to pumping mechanism for hydraulic cylinders and is particularly adapted to jacks, presses and pullers.

The primary object of the invention is to provide an oil reservoir that will be maintained in an upright position so that the oil can be pumped out of the same without encountering air pockets.

Heretofore pumping mechanisms have been incorporated including their reservoir within the hydraulic assembly in a fixed relative position and when the hydraulic assembly was inverted or otherwise held at an angle, air was taken into the suction line due to the position of the suction pipe relative to the oil level within the reservoir, but with my new and improved reservoir the same is suspended on a flexible hose so that the reservoir and the suction line will be maintained in a vertical position so that the suction end of the hose is always under the oil level.

These and other incidental objects will be apparent in the drawing, specification and claims.

Referring to the drawing:

Figure 1 is a side elevation of a typical hydraulic jack having my new and improved reservoir attached thereto, parts broken away for convenience of illustration.

Figure 2 is an enlarged fragmentary plan cross sectional view of the jack taken on line 2—2 of Figure 1.

Figure 3 is a sectional view taken on line 3—3 of Figure 1, parts broken away for convenience of illustration.

Figure 4 is a further illustration of the jack being used as a puller. This view demonstrates that the reservoir unit is always in a vertical position regardless of the position of the jack.

My new and improved portable hydraulic jack comprises a working cylinder 1 having an open end that is closed by a cap nut or plug 1a. A pump cylinder 2a of the pump mechanism 2 is formed integral with the outer wall of the cylinder 1 with the longitudinal axis of the mechanism in parallel relation to the longitudinal axis of the working cylinder. A transversely or laterally extending valve chamber 3 is formed on the lower end of the pump cylinder 2a integral therewith and with the outer wall of the cylinder 1. Positioned in one end of the chamber 3 is the spring biased inwardly opening inlet valve 4 which is retained in its proper position by means of the set screw 4a. Connected to one end of the chamber 3 and communicating therewith is the flexible supply line 5 which at its opposite end is connected to the reservoir 6. The opposite end of the chamber 3 is closed by a cap nut or plug 55

3a and inwardly of the plug 3a is the spring biased outlet valve 7. An inlet port 8 provides communication between the cylinder 1 and the chamber 3 and is controlled by means of the valve 1.

5 It will be understood that the valves 4 and 7 are accessible through the plug 3a for the removal or insertion thereof as is necessary for repair purposes.

10 Mounted for reciprocal operation within the cylinder 1 is the plunger or ram 9 which is operated by hydraulic fluid 14. A stuffing box 10 at the closed end of the cylinder 1 cooperates with the ram 9 to prevent leakage of the hydraulic fluid from the cylinder 1. The ram 9 is provided at one end with a tool receiving socket or bore 11 which receives a tool 12 therein. It being understood that other tools than the one disclosed are susceptible of being inserted into the socket 11.

15 20 The flexible supply line 5 has an extension 13 at the end connected to the reservoir 6 which extends through the top of the reservoir 6 down through the fluid 14 to a point slightly spaced from the bottom of the reservoir 6 to provide a clearance 15 for the passage of the fluid 14 into the extension 13 (Fig. 1). A removable plug 6a in the top of the reservoir 6 permits the replenishing of the fluid 14 as is found necessary.

25 30 A bleeder valve 16 closes or opens the bleeder port 17 which is closed at the outside by a plug 17a. The port 17 leads from the inlet end of chamber 3 outwardly of the check valve 4 between the latter and the supply line 5. The valve 16 being normally closed and opened when it is desired to allow the fluid 14 to drain from the cylinder 1 back into the reservoir 6, the operation of which I will more fully describe later.

35 40 45 Pivotedly connected to the outer wall of the cylinder 1 at one end by means of the pivot pin 20a is a link 20. The opposite end of the link 20 is pivotedly connected at 19 to one end of a handle 18 which is pivotedly connected at 22 to the bifurcated end 21a of a plunger or piston 21. The piston 21 being reciprocally mounted in the pump cylinder 2a of the pump mechanism 2.

45 50 Formed integral with the outer wall of the cylinder 1 on opposite sides thereof on a line below the pump cylinder 2a are the pair of parallel cross arms 26 the ends of which extend in opposed parallel relation to each other in opposite directions from the cylinder 1. Each of the cross arms 26 is provided with a plurality of relatively spaced openings 27a which extend from the ends of each arm to the merging of the cross arms 26 with the cylinder 1.

I will now describe the operation of my new and improved hydraulic jack. When it is desired to operate the plunger or ram 9 within the cylinder 1 the pump handle 18 is operated in a conventional pumping action. Movement of the handle 18 will reciprocate the piston 21. When the handle 18 and piston 21 are raised the check valve 4 is opened by reason of the suction created in pump cylinder 2a. This suction will draw the fluid 14 into the pipe 13 through the space 15 and the fluid 14 will travel through the flexible tube 5 into the valve chamber 3. When the handle 18 is pressed downwardly the inlet valve 4 will be closed and the outlet valve 7 will be opened allowing the fluid 14 to be forced through the inlet port 8 into the cylinder 1 extending the ram 9. The extension of the ram 9 depending on the number of times the handle 18 is raised or lowered.

When it is desired to release the fluid from the cylinder 1 the valve 16 is opened allowing the fluid to drain through the port 17 back into the flexible supply line 5 and to return to the reservoir 6.

In Fig. 1 my hydraulic jack is disposed vertically and is used as a raising device wherein the tool 12 is placed on the fixed support 30 so that the object 31 may be raised as desired.

In Fig. 4 my hydraulic jack is disposed horizontally and is being used as a puller. In this position the tool 12 contacts the end 23 of a shaft 24. Pulling hooks 25 are bolted to the cross arms 26 intermediate thereof by means of bolts 27 passing through the spaced openings 27a in both arms. The ends 28 of the hooks 25 engage the element 29 which is desired to be removed from the shaft 24. Regardless of the manner of use of the jack, the operation of the jack is as previously described.

It makes no difference whether the jack is being operated in a vertical position as in Fig. 1 or a horizontal position as in Fig. 4 the position of the oil reservoir 6 is always vertical and this is the primary object of my invention. However, I do not wish to be limited to the illustration of Figs. 1 and 4 as it may be adapted to many other positions and operations.

It is also to be understood that certain changes in the mechanical details may be made provided they fall within the scope of the appended claims.

What I claim is:

1. A portable hydraulic jack comprising in combination a working cylinder, a ram reciprocable in said working cylinder, a pump cylinder formed integral with the outer wall of the working cylinder, a valve chamber integral with the outer wall of the working cylinder and extending laterally of the pump cylinder, at the lower end

thereof, a communicating passage between said working cylinder and said pump cylinder by way of said valve chamber, a pump piston in said pump cylinder, a normally closed spring biased inlet pump valve in one end of said valve chamber which opens inwardly with respect to that end of the valve chamber, a normally closed spring biased outlet pump valve in said working cylinder and pump cylinder communicating passage and located in the opposite end of said valve chamber to open outwardly with respect to that end of the valve chamber, a bleeder port in said working cylinder forming a communicating passage between the working cylinder and the valve chamber outwardly of the inlet pump valve, an independent portable reservoir free of the working cylinder, and a flexible connection between said reservoir and the inlet end of said valve chamber whereby said reservoir may be retained in a vertical position regardless of the position of said working cylinder.

2. A hydraulic jack comprising a working cylinder, a plunger movable in said working cylinder and extending through a packing at one end thereof, a pump cylinder lengthwise on and between the ends of the working cylinder, a valve chamber at and communicating with one end of the pump cylinder, a piston operable in the pump cylinder, said valve chamber having an inlet at one end and an outlet at the other end communicating with the working cylinder between its ends, an inlet valve in the inlet opening into the chamber, an outlet valve at and opening toward the outlet, said pump communicating with said valve chamber being located between said inlet and outlet valves, a valved bleeder port between the inlet outwardly of the valve therein and the end of the working cylinder adjacent the inlet end of said valve chamber, a portable reservoir independent of the cylinders, and a flexible tube extending between the reservoir near its bottom and the inlet.
